UNITED STATES PATENT OFFICE.

ALBERT H. DE VOE, OF WESTFIELD, NEW JERSEY, ASSIGNOR TO THE SINGER
MANUFACTURING COMPANY, A CORPORATION OF NEW JERSEY.

DIFFERENTIAL FEEDING MECHANISM.

1,317,005.

Specification of Letters Patent. Patented Sept. 23, 1919.

Application filed September 30, 1916. Serial No. 122,954.

To all whom it may concern:

Be it known that I, ALBERT H. DE VOE, a citizen of the United States, residing at Westfield, in the county of Union and State 5 of New Jersey, have invented certain new and useful Improvements in Differential Feeding Mechanisms, of which the following is a specification, reference being had therein to the accompanying drawings.

10 This invention relates to an improvement of that type of differential feeding mechanism for sewing machines, in which two feed-dogs are given equal feed-and-return movements and differential rising-and-falling movements; and it has for an object to provide mechanism of the class described 15 which shall be compact, durable and effective, and which shall comprise relatively few operative parts.

20 In the present embodiment of the invention a primary or forwardly disposed feed-dog is carried by a feed-bar or primary lever which is fulcrumed on a feed-rocker and derives its rising-and-falling movements 25 from an eccentric on the main-shaft. The feed-rocker is fulcrumed on the machine frame and is actuated by another eccentric on the main-shaft. The secondary or rearwardly disposed feed-dog is adjustably 30 mounted on the forward end of the secondary feed-bar or lever which extends alongside the primary feed-bar and is pivoted between its ends to the latter. The rearwardly extending end portion of the secondary 35 feed-bar is provided with a curved slot and is anchored to a fixed point on the frame by a single link carrying a pin at its upper end which is secured in adjusted position within said slot by a thumb-nut.

40 In the drawings, Figure 1 is a plan view of the mechanism embodying the present improvement. Fig. 2 is a rear elevation of the same. Fig. 3 is a side elevation and Figs. 4, 45 and 6 are side views showing the relative positions of certain of the operative parts in successive stages of the feeding cycle.

In the preferred embodiment of the invention, as illustrated, the supporting frame 1 is formed with sleeved bearing lugs 2—2 50 1 in which are journaled the opposite ends of the fulcrum-pin 3 rigidly secured within the alined apertures in the downwardly projecting spaced lugs 4—4 of the feed-rocker 5. The upper extremity is formed with 55 spaced bearing bosses 6—6 for the support-

ing pin 7 rigidly secured within the alined apertures in the rearwardly projecting spaced lugs 8—8 of the main feed-bar or lever 10 which, in the present instance, is in the form of a rectangular frame. Projecting forwardly from one corner of the frame 10 is an apertured boss 11 within which is rigidly secured the pin 12 whose forwardly projecting extremity enters the usual sleeved eccentric strap 13 surrounding the feed-lift eccentric 14 on the main shaft 15 journaled in suitable bearings, one of which is shown at 16. The feed-rocker is extended forwardly at one side to form an apertured boss 17 within which is secured 60 the pin 18. The main-shaft carries an adjustable feed-advancing eccentric 19 of common form to which is fitted a sleeved eccentric strap 20 adapted to slidingly receive the forwardly projecting end-portion of the pin 75 18. Mounted within the guideway 21 at the forward extremity of the main feed-bar 10 is the shank 22 of the main feed-dog 23 which projects upwardly and forwardly 80 from the free end of the feed-bar 10 and is serrated as usual along its active upper surface 24 which at times is projected above and withdrawn below the upper surface of the throat-plate 25 by the action of the feed-lift eccentric, as is well understood.

85 The secondary or rearwardly disposed feed-dog 26 is smaller and in the present instance is adapted to feed the work a shorter distance than the main feed-dog 23 during each feeding cycle. To this end the secondary feed-dog 26 is formed with a downwardly extending slotted shank 27 adjustably secured in the forward end of the secondary feed-bar 28 extending rearwardly 90 alongside of the main feed-bar 10 and terminating adjacent one of the bearing lugs 6. The secondary feed-bar is formed between its ends with a bearing boss 29 which is entered and supported by the screw-pin 30 threaded into the main feed-bar 10. The 100 rearward end-portion of the secondary feed-bar 28 is provided with a curved slot 31 within which is slidingly fitted a flattened portion 32 of the fulcrum-screw 33, Figs. 1 and 3, journaled in the apertured upper extremity of the anchor-link 34 whose lower apertured extremity freely surrounds and is supported by the pivot-pin 3 of the feed-rocker 5, between the right-hand boss 4 and lug 2, Fig. 2. The fulcrum-pin 33 has a re- 105 110

duced and threaded extremity 35 which projects through the slot 31 and carries a thumb-nut 36 serving to clamp the fulcrum-screw 33 rigidly to the secondary feed-bar 5 in any desired position of adjustment along the slot 31. A washer 37 is interposed between the thumb-nut 36 and the secondary feed-bar 28, as shown in Fig. 1.

- In the position of the parts shown in Figs. 10 1 and 3 the fulcrum-screw 33 is adjusted to the rearward extremity of the slot 31 and the axis of the screw 33 is nearly coincident with the axis of the pivot-pin 7 on the main feed-bar. As a result the two 15 feed-dogs 23 and 26 are moved substantially as one throughout the feeding cycle. When the fulcrum-screw 33 is adjusted to the other extremity of the slot, as shown in Fig. 4, the rising-and-falling movements of the 20 secondary feed-dog 26 are differentiated from the corresponding movements of the primary feed-dog 23. In Fig. 4 the feed-dogs are at the point of emerging simultaneously above the upper surface of the throat-plate 25 and the feed-rocker 5 have nearly 25 reached its extreme forward position indicated by the dotted circle *f*. At this point in the cycle the curved slot 31 is concentric with the axis of the pivot-pin 3 and it will 30 thus be seen that the feed-dogs will always be projected substantially simultaneously above the surface of the throat-plate, regardless of the position of adjustment of the fulcrum-screw 33.
- 35 When the feed-dogs are at the point of beginning an effective feeding stroke, having moved forward slightly from the position shown in Fig. 4, they will assume different elevated positions above the throat-plate, as shown in Fig. 5. The rising pin 30 carried by the main feed-bar 10 will have rocked the secondary lever 28 and lifted the feed-dog 26 above the level of the primary feed-dog 23. This differential lifting action 40 occurs because the distance between the pin 30 and the fulcrum-screw 33 is less than the distance between the pin 30 and the fulcrum-pin 7.
- 45 In moving from the position shown in Fig. 5 to that shown in Fig. 6, wherein the secondary feed-dog is shown disappearing below the level of the throat-plate, the feed-rocker will have moved about three-quarters of the distance to the rearward extremity of its throw indicated by the dotted circle *r*. It will thus be seen that the feed dog 26 becomes ineffective while the primary feed-dog 23 still occupies a position above the throat-plate intermediate the extremes of its effective feeding stroke. The 50 rapid falling movement of the feed-dog 26 is caused partly by the falling movement of the feed-bar 10 and partly by the feed-advancing movement of the feed-bar 10 55 which will impart a corresponding length-

wise movement to the feed-bar 28. This movement will rock the anchor-link or differentiator 34 toward a vertical position indicated by the line *t* and consequently raise the fulcrum-screw 33 to a higher position, 70 thus lowering the feed-dog 26.

It is to be understood that the usual foot 38 pressed downwardly by a spring (not shown) coöperates with the forward feed-dog 24 to advance the work, while a secondary presser-foot 39, mounted on the foot 38 for yielding movements relative thereto, is provided to coöperate with the feed-dog 26. The secondary presser-foot 39 is mounted directly in rear of the needle *n* 80 and has a cylindrical shank 40 which slides in an apertured bearing boss 41 formed on the shank of the main foot 38. A collar 42 limits the downward movement of the foot 39 under the influence of the coiled spring 43; the limit of upward movement of the foot 39, relative to the foot 38, being determined by the lower end of the bearing boss 41. The spring 43 surrounds a guide-pin 44 fixed to the shank of the main foot 38 and the lower end of said spring is received within a recess in the upper surface of the foot 39.

It will be seen that the present embodiment of the invention utilizes, in addition to the well known four-motion feed, but two essential parts, *i. e.*, a secondary feed-member and an anchor-link, or differentiator, to secure a differential feeding action. The construction is thereby rendered extremely simple and compact.

Having thus set forth the nature of the invention, what I claim herein is:

1. Differential feeding mechanism for sewing machines comprising, in combination, a supporting frame, a primary feed-bar carrying a feed-dog, a secondary feed-bar carrying a feed-dog and pivoted to said primary bar for differential rising and falling movements relative thereto, said secondary feed-bar having a slot, and adjustable connections between said slot and frame for varying the said differential movements.

2. Differential feeding mechanism for sewing machines, comprising, in combination, a frame, primary and secondary feed-dogs, carriers therefor, one of said carriers being supported by the other for differential rising-and-falling movements and substantially equal feed and return movements, means for actuating one of said carriers, and a link directly connecting the other of said carriers with the frame.

3. Differential feeding mechanism for sewing machines comprising, in combination, a frame, pivotally connected primary and secondary feed-bars carrying feed-dogs, means for actuating one of said bars and a single pivoted link bar directly connecting

the other of said feed-bars to the frame, and arranged to swing in the plane of work-engaging movement of the feed-dogs.

4. Differential feeding mechanism for

- 5 sewing machines, comprising, in combination, a frame, primary and secondary feed-dogs, primary and secondary levers carrying said feed-dogs and pivotally connected together for differential rising-and-falling movements relative to one another, actuating mechanism for imparting operative movements to said primary lever, and a single upright anchoring link pivotally connected at its upper end to said secondary lever and at its lower end to the frame.

5. Feeding mechanism for sewing machines comprising, in combination, a supporting frame, primary and secondary feed-bars pivotally connected for differential rising and falling movements, means for imparting four-motion movements to said primary feed-bar, a link connected at one end directly to the frame and at its opposite end directly to said secondary feed-bar, and 25 means whereby the distance of the point of connection between said secondary feed-bar and said link from the pivotal connection of said feed-bars may be varied.

6. Differential feeding mechanism for

- 30 sewing machines, comprising, a frame, primary and secondary feed-levers extending substantially in the same direction throughout their length and pivotally connected together between their ends, a feed-dog carried at the forward end of each of said levers, a feed-rocker pivoted to the frame and supporting the rear end of said primary lever, means for raising and lowering said primary lever and a link directly 35 connecting said secondary lever with the pivotal connection between the feed-rocker and the frame.

7. Differential feeding mechanism for 40 sewing machines comprising, primary and secondary feed-dogs, means for imparting

equal feed-and-return and differential rising-and-falling movements to said feed-dogs, the parts being so constructed and arranged that the operative surfaces of the feed-dogs are projected substantially simultaneously above the throat-plate, and means whereby said differential movements may be adjusted without varying the relative timing of the projection of said feed-dogs above the throat-plate.

55 8. Differential feeding mechanism for sewing machines, comprising, a frame, a primary lever carrying a feed-dog, means for imparting four motions thereto, a slotted secondary lever carrying a feed-dog, connections between said levers, whereby operative movements imparted to said primary lever are transmitted to said secondary lever, a link connected at one end to a fixed point on the frame, a pin carried by said link 60 and adjustably secured within the slot in said secondary lever, said slot being substantially concentric with said fixed point when the active surfaces of the feed-dogs are substantially coincident with the upper surface of the throat-plate.

65 9. Feeding mechanism for sewing machines comprising, in combination, a frame, a feed-bar, two feed-dogs carried by said feed-bar for differential times of contact 70 with the work and a single positioning link between one of said feed-dogs and the frame.

75 10. In a sewing machine, in combination, a frame, a reciprocating fulling-feed, a stitch-spacing feed, carried by said fulling-feed, said feeds having substantially equal feed and return movements, and a single positioning link between said stitch-spacing feed and the frame of the machine for differentiating the times of work engaging 80 contact of said feeding members.

85 In testimony whereof, I have signed my name to this specification.

ALBERT H. DE VOE.
